FIG. 3.

FIG. 4.

FIG. 2.

INVENTOR
MILTON S. HUFSCHEIDT

BY *Strong & Townsend* ATTORNEYS

UNITED STATES PATENT OFFICE.

MILTON S. HUFSCHEIDT, OF SAN FRANCISCO, CALIFORNIA.

SANITARY FLUSHING-NOZZLE.

1,366,320.

Specification of Letters Patent. Patented Jan. 18, 1921.

Application filed April 30, 1919. Serial No. 293,648.

To all whom it may concern:

Be it known that I, MILTON S. HUFSCHEIDT, a citizen of the United States, residing at the city and county of San Francisco and State of California, have invented new and useful Improvements in Sanitary Flushing-Nozzles, of which the following is a specification.

This invention relates to a sanitary flushing nozzle and especially to a syringe adapted to be used for irrigating and cleansing the vaginal canal.

One of the objects of the present invention is to provide a syringe of the above character which is simple and substantial in construction and provided with adjustable and detachable parts which may be readily separated and sterilized.

Another object of the invention is to provide a syringe by which the water or liquid employed may be efficiently applied, and furthermore a syringe equipped with a return flow or discharge connection through which the liquid may freely escape during the cleansing operation.

Another object of the invention is to provide means for imparting a pulsating movement to the liquid passing through the discharge nozzle of the syringe.

Further objects will hereinafter appear.

The invention is illustrated, by way of example, in the accompanying drawings in which:

Figure 1 is a side elevation of the sanitary flushing nozzle.

Fig. 2 is a side elevation showing how the sanitary nozzle is connected with a source of water supply and also how it is connected with a return or discharge connection.

Fig. 3 is a detailed view showing a slight modification of the form of nozzle shown in Fig. 1.

Fig. 4 is a detailed view of the nozzle proper.

Referring to the drawings in detail and particularly to Fig. 1, A indicates a holder in which is formed two passages indicated at 2 and 3. Forming an extension of the outer end of the holder is a pair of nipple members 4 and 5 to which a pair of rubber tubes will be connected as hereinafter described. Formed on the opposite end of the holder is a recess 6 for the reception of a nozzle 7 and formed at the same end of the holder in alignment with the opening 6 is a collecting pocket 8 which is in connection

with the passage 3 and the nipple 5. Surrounding the holder and suitably secured thereto is a resilient plug member generally indicated at 9. This member is constructed of rubber, or other flexible material, and serves the purpose of forming a closure for the opening into which the nozzle 7 is inserted as will hereinafter be described. The nozzle 7 consists of a tube or a member which is slightly curved, as shown in Fig. 1. This member is provided with an interior passage 10 and the outer end of the same is provided with a plurality of discharge openings 11 through which the water or other liquid employed may freely flow when the device is being employed. The outer end of the nozzle is closed and the only discharge opening provided is therefore the plural openings shown at 11. These openings are radially disposed and terminate in grooves 12, formed on the outer end of the nozzle. The inner end of the nozzle is cylindrical in cross sections and is tapered, as shown at 13, to permit the nozzle to be inserted in a socket formed in the holder for its reception. The method of supporting and securing the nozzle is important as it permits adjustment of the same or turning of the nozzle to suit varying conditions.

By referring to Fig. 2, it will be seen that the sanitary flushing nozzle is connected with a hot-water bag 14 by means of a rubber tube 15, this tube being equipped with a hand-bulb 16 and a cut-off or clamp 17. The tube 15 is connected with the nipple 4 and water contained in the bag 14 will therefore drain downwardly through the tube and will then pass through the nipple 4, the passage 2 and the passage formed in the nozzle 10, the water being finally permitted to escape through the radially disposed openings 11 and the grooves 12 formed in the nozzle tip. Water is in this manner sprayed in all directions against the internal walls of the canal into which it is inserted, and it is furthermore permitted to drain and discharge through the holder, as this is provided with a return connection or tube 18, that is, the pressure created by the entering water will very slightly expand the walls and will therefore permit the water to drain freely in a downward direction until it enters the recess 8 and the passage 3 formed in the holder. From here it is obvious that it will drain with a slight suction through the nipple 5 and the tube 18. If it is desired

to insure a more vigorous application of water or other liquid it is only necessary to compress the hand-bulb 16. This produces a pulsating flow and alternately increases and decreases the pressure of the water discharged through the perforations 11 formed on the outer end of the nozzle.

A syringe construction, as here shown, is not only simple and compact but its construction permits it to be quickly assembled and taken apart for use or for cleansing and sterilization of same.

The syringe is particularly constructed for insertion into the abdominal cavities and discharge passages of the human body. The connection formed between the syringe and the source of water or other liquid supply permits a continuous circulation of a large volume of liquid to every part of the cavity treated. A variable flow or alternation from high to low pressure of the liquid is of great importance as it causes a contraction and expansion of the mucous membrane of the walls of the cavity. It furthermore produces a scrubbing and massage effect which not only causes a thorough cleansing but also circulation of blood in the surrounding tissues, in this manner alleviating and often curing diseases of parts treated. The resilient nature of part 9 permits the abdominal cavity treated to be entirely closed when the cleansing operation is taking place, thus permitting the user to lie in bed, to stand or to assume any position desired when using the same. It will furthermore be seen that soiling of the bedding or wearing apparel is also obviated as the water, after having performed its cleansing operation, is automatically discharged through the tube 18. A slight suction completely empties the cavity of all liquids. While the form of nozzle shown in Fig. 1 is curved, I wish it understood that it may be straight as shown in Fig. 4, and I also wish it understood that the design and the shape of the same may be altered to suit varying conditions and applications. By referring to Fig. 1, it can be seen that the holder serves the function of supporting the flexible plug 9 and also the nozzle 7. By referring to Fig. 3, which is a modification of the same, it will be seen that the flexible plug member indicated at 9 serves the function of supporting the nozzle 7 and also the nipple member 5. In other words, the holder proper is entirely limited, as the rubber plug may serve the same function. The nozzle 7 may therefore be removed if desired or it may be turned to any position. The nipple 5 may also be removed, thus permitting cleaning and sterilization of the parts more readily than with the structure shown in Fig. 1.

I therefore wish it understood that the material and finish of the several parts of the device could be such as the experience and judgment of the manufacturer may dictate; also that various changes in form and minor details of construction may be resorted to within the scope of the appended 70 claims.

Having thus described my invention, what I claim and desire to secure by Letters Patent is:

1. An apparatus of the character described comprising an elongated substantially cylindrical shaped holder having an inlet and a discharge passage formed therein and extending therethrough, a collecting pocket communicating with the receiving end of the discharge passage, a flexible guard surrounding the holder and adjustable longitudinally thereon, a curved spray nozzle having a tapered end fitted to the inlet passage of the holder and turnable therein, and a pair of extensions on the opposite end of the holder in which the inlet and discharge passages terminate, said extensions being disposed on an angle with relation to each other and forming tube connecting members. 90

2. In an apparatus of the character described a substantially cylindrical shaped elongated holder, said holder terminating at one end in a pair of extensions for the attachment of flexible tubes, an inlet passage 95 and an outlet passage formed in the holder and terminating one in each extension, a flexible guard member longitudinally adjustable on the holder and a nozzle insertible in the holder and adapted to communicate with the inlet passage. 100

3. An apparatus of the character described including a holder having inlet and discharge passages formed therein and extending therethrough, a collecting pocket 105 communicating with the receiving end of the discharge passage, a flexible, compressible plug surrounding and carried by the holder, a curved spray nozzle having a tapered end fitted to the inlet passage of the holder and 110 turnable therein, a series of holes formed in the sides of the nozzle near the outer end, and a series of grooves or channels formed in the exterior surface of the nozzle with which said holes communicate and by which 115 the discharge is directed outside of the nozzle to the collecting pocket and thence through the holder to a discharge.

In testimony whereof I have hereunto set my hand in the presence of two subscribing 120 witnesses.

MILTON S. HUFSCHEMIDT.
